P. HYNDMAN

WAGON SEAT

Filed Nov. 26, 1926

Inventor

P. Hyndman

By

P. Hyndman

UNITED STATES PATENT OFFICE.

PETER HYNDMAN, OF BALCARRES, SASKATCHEWAN, CANADA.

WAGON SEAT.

Application filed November 26, 1926. Serial No. 150,981.

The invention relates to improvements in wagon seats and particularly to improvements in means for suspending the seat from a wagon box, and an object of the invention is to provide a spring seat having hangers which can be adjusted to accommodate the height of the sides of the box to permit the seat to take a convenient location in respect to the bottom of the box and 10 make it comfortable for one sitting on the same.

A further object is to construct the hangers so that they can be readily folded to permit the seat being used on a loaded 15 box.

A further object is to construct the device in a simple, durable and inexpensive manner.

With the above more important objects in view the invention consists essentially in the 20 arrangement and construction of parts, hereinafter more particularly described, reference being had to the accompanying drawing, in which:

Fig. 1 is a perspective view of the complete device showing the hangers in their 25 fully extended position.

Fig. 2 is an end view of the seat showing it as it appears suspended from the sides of a loaded box.

Fig. 3 is an end view of the seat as it 30 appears suspended from what is known as a two deck box.

Fig. 4 is a vertical cross sectional view through what is known as a three deck box 35 and showing the seat suspended therein, the seat hangers in this view occupying the same position as appearing in Figure 1.

Fig. 5 is a view showing the manner in 40 which the lower sections of the hangers fold in underneath the spring supporting bar.

In the drawing like characters of reference indicate corresponding parts in the several figures.

It is a well known fact that wagon boxes 45 are provided with sets of side boards which permit the depth of the box to be varied according to the produce to be loaded therein. Where the sides of the box are one board high it is known as a one deck box, where it is two boards high as a two deck 50 box and where it is three boards high as a three deck box.

It is desirable for a farmer or such person 55 to have a spring seat which can be adjusted to accommodate the number of decks used on the wagon box so that he may sit com-

fortably in relation to the bottom of the box, and the present invention provides such a device.

The seat 1 is of the ordinary type and 60 presents the upstanding side and end rests 2. Each end of the seat is provided at the corners with vertical holes or slots 3 and 4, these being formed in the present instance by notching out the corners of the seat and 65 securing a piece of strap iron 5 to the seat, as shown best in Figure 1. Each end of the seat is provided with the parts now described. A pair of hangers 6 and 7 are supplied and each hanger presents a comparatively short upper section 8, a central section 9 and a lower section 10, the sections being pivotally connected one to the other at 11 and 12 and preferably by counter sunk 70 rivets.

The upper end of the upper section is provided with an out turned hook or supporting catch 13 and the lower end of the lower section terminates in a head 14, which in the present instance is in the form of a 80 T. It will be observed also that the upper end of the lower section extends a short distance beyond the pivot point 12 to provide locking means later described, and it will be also noticed that in one instance the 85 section 10 is attached to the inner side of the section 9, whilst in the other case it is attached to the outer side of said section. The hangers are adapted to pass slidably through the slots 3 and 4 when in their extended 90 position.

The lower ends of the sections 10 pass 95 slidably through suitable slots 15 and 16 provided in a spring supporting bar 17, which in the present instance is of angle iron cross section presenting a horizontal and vertical flange. A helical spring 18 is permanently riveted at 19 and 20 to the horizontal flange of the bar and to the under side of the seat end. The ends of the bar 17 are provided with catches or hooks 21 and 22 pivotally secured thereto by a loose rivet 23, and these hooks are designed so that they can take an in swung or out 100 swung position as shown in the several figures.

When a one, two or three deck wagon is 105 loaded with produce, one slides the hangers through the slots 3 and 4 and those 15 and 16 until the intermediate sections 9 take a position between the seat and the spring supporting bars, or as shown in Figure 2, and he then swings the lower section inwardly 110

into a horizontal stacked or stored position underneath the horizontal flanges of the bars 17, in which position they are shown in Figure 2. In this position it will be observed that the projecting ends 10' of the lower sections 9 from pulling upwardly through the slots. One swings also the upper sections 8 of the hangers inwardly to the position shown in Figure 2 to overlie the ends of the seat and he also swings the hooked catches 21 and 22 outwardly to hook over the upper edge of the wagon box 24.

The seat will be so suspended when used also on a one deck wagon box.

When it is desired to use the seat on a two deck wagon box the lower hanger sections are retained in their folded position, but one swings the upper sections 8 to their horizontal position and also turns the catches 21 and 22 inwardly and the parts are as shown in Figure 3. The hooked catches 13 are caught on the upper edges of the sides of the two deck wagon box and suspend the seat in the position shown in Figure 3.

Where a three deck wagon box is used the hangers are fully extended and the catches 21 and 22 are turned inwardly and the seat is suspended from the sides of the three deck box by the hooks 13 which are caught over the upper edges of the upper side boards of the three deck wagon box and in the manner as shown in Figure 4.

In all of these various conditions it will be observed that the seat is retained in a relatively constant position in respect to the bottom 25 of the wagon box so that the one occupying it is at all times comfortably seated.

What I claim as my invention is:—

1. In combination, a wagon seat having slots in the corners thereof, elliptical springs underlying and secured to the ends of the seat, side bars underlying and secured to the springs, similar pairs of end hangers passing slidably through the slots in the ends of the seat and slidably through aligned slots provided in the side bars, said hangers having their upper ends hooked and their lower ends enlarged and being formed from pivotally jointed sections.

2. In combination, a wagon seat having slots in the corners thereof, elliptical springs underlying and secured to the ends of the seat, side bars underlying and secured to the springs, similar pairs of end hangers passing slidably through the slots in the ends of the seat and slidably through aligned slots provided in the side bars, said hangers having their upper ends hooked and their lower ends enlarged and being formed from pivotally jointed sections and hook supports pivotally attached to the ends of the side bars.

Signed at Balcarres this 10th day of May, 1926.

PETER HYNDMAN.
